UNITED STATES PATENT OFFICE.

JOSEPH BRYERS, OF CHICAGO, ILLINOIS.

COMBINED MEDICINE-MEASURE AND CORKSCREW.

No. 880,505.

Specification of Letters Patent.

Patented March 3, 1908.

Application filed November 20, 1907. Serial No. 402,977.

To all whom it may concern:

Be it known that I, JOSEPH BRYERS, a citizen of the United States, residing at Chicago, county of Cook, and State of Illinois, have 5 invented certain new and useful Improvements in a Combination Medicine-Measure and Corkscrew, of which the following is a specification.

My invention relates to a combined medicine measure and cork screw.

The object of my invention is to provide a medicine measure having the form of the measuring glass or graduate and equip the same with a cork screw arranged in the stem 15 thereof.

A further object of my invention is to provide a device as mentioned having a folding stand or base.

A further object of my invention is to provide means for retaining the cork screw within the stem except when desired for use.

Other objects will appear hereinafter.

My invention will be more readily understood by reference to the accompanying 25 drawings forming a part of this specification and in which,

Figure 1 is a perspective view of a combined measuring glass and cork screw embodying my invention, Fig. 2 is a vertical 30 section thereof, a portion of the stem being shown in elevation, Fig. 3 is a section on the line $x-x$ of Fig. 1, and Fig. 4 is a detail sectional view of a modified form.

Referring to the drawings, 1 indicates a 35 graduated measure for medicines or other fluids. This is preferably conical and is provided with a stem, 2 which is preferably cylindrical and which is provided with a recess, 3, within which is pivotally mounted 40 as at 4, a cork screw, 5. When the cork screw is not in use, it lies within the recess, 3 but when it is desired to use the same it may be readily turned into the position shown in dotted lines in Fig. 2.

45 6 indicates a cylindrical member or sleeve loosely mounted upon the stem, 2 and provided with an aperture, 7 adapted in one position to register with the recess, 3. When the cork screw is within the stem, the sleeve, 50 6 may be turned to close the recess and retain the cork screw. Pivotally connected to the lower end of the stem, 2 is a base or

stand, 8 having a radial recess, 9 to receive the stem when turned into the position shown in dotted lines in Fig. 2. The sides 55 of the recess, 9 are curved, forming claw shaped portions, 9' which are sharpened and serve to cut the string or wire, which sometimes fastens the cork in the bottle.

The measure proper may be formed of 60 metal and the graduations indicated thereon by a series of indentations 10. However, if preferred this portion of the device may be formed of glass having the usual etched 65 graduations. To this end, the upper portion of the stem is formed with a conical recess, 11, to receive the lower end, 12 of the glass graduate, 13. The graduate is cemented in the socket 11 but to more securely fasten it therein, I provide the lower end of 70 the graduate with an annular groove, 14 which is engaged by a rim or bead, 15 on the socket portion, 11.

Having described my invention what I claim as new and desire to secure by Letters 75 Patent is:

1. A graduate having a stem and a base, in combination with a cork screw pivotally connected thereto and adapted to swing into position parallel with said stem and a member 80 rotatably mounted on said stem for holding said cork screw in parallel position therewith, substantially as described.

2. A graduate having a stem and a base, said stem having a longitudinal recess, a cork 85 screw pivotally mounted in said recess and an apertured sleeve loosely mounted on said stem and adapted in one position to open said recess and in another to close the same, substantially as described. 90

3. A graduate having a stem and a base pivotally connected to said stem, in combination with a cork screw pivotally connected thereto, said base having a radial recess to receive said stem when the cork screw is extended for use, substantially as described. 95

In testimony whereof I have signed my name to this specification in the presence of two subscribing witnesses.

JOSEPH BRYERS.

Witnesses:

AGUSTA J. BRYERS,
FRANCES E. SHEEHY.
